UNITED STATES PATENT OFFICE.

JAMES E. DEERING, OF EVANSTON, ILLINOIS.

HARVESTER ELEVATOR-FRAME.

SPECIFICATION forming part of Letters Patent No. 403,094, dated May 14, 1889.

Application filed October 19, 1886. Serial No. 216,619. (No model.)

To all whom it may concern:

Be it known that I, JAMES E. DEERING, a citizen of the United States, residing at Evanston, in the county of Cook and State 5 of Illinois, have invented certain new and useful Improvements in Harvester Elevator-Frames, which are fully set forth in the following specification, reference being had to the accompanying drawings, forming a part 10 thereof, wherein—

Figure 1 is a front elevation showing the side boards partly broken away to uncover the interior parts. Fig. 2 is a rear elevation with the side boards similarly broken away. 15 Fig. 3 is a section through xx in Fig. 2. Fig. 4 is a perspective of the frame with the elevating-canvases removed.

A' is the rear sill or frame-bar of the harvester.

20 A^2 is the front sill.

B' , B^2 , B^3 , and B^4 are upright corner-posts at the inner forward, outer forward, inner rear, and outer rear corners, respectively, of the elevator-frame.

25 $C' C^2$ are respectively the forward and rear side boards of the elevator-frame.

$D' D'$ and $D^2 D^2$ are respectively the lower and upper slide-bearings for the canvas elevating-belts. Said bars D' and D^2 are com- 30 monly called the "canvas-slides," and will be so hereinafter designated.

35 D^{10} and D^{20} are respectively the upper and lower canvases or elevating-belts. They are provided in the usual manner with the cross-strips d , which prevent the bagging of the canvases in the middle, and which bear on the canvas-slides D' and D^2 , and thereby enable said slides to somewhat control the course 40 of the canvases.

45 $E' E^2$ are sheet-metal plates placed on the inner surface of the side boards, $C' C^2$, respectively, as linings for the elevator-frame. The canvas-slides are secured inside said lining-sheets $E' E^2$, the fastening being most effectively made by bolts which pass through the canvas-slides and the lining-sheets and the side boards, and obtain their fastening in

the corner-posts $B' B^2 B^3 B^4$. The same bolts thus become the fastenings, also, of the metallic lining-sheets $E' E^2$, which are thus bound 50 with the side boards, $C' C^2$, between the corner-posts on the outside and the canvas-slides on the inside.

The metallic sheet-linings $E' E^2$ serve the purpose of rub-irons, to prevent the canvases 55 and the cross-strips wearing into the side boards, and thereby also diminishing the friction which would be caused simultaneously with such wear. Said metallic lining-sheets also serve the purpose of strengthening and 60 stiffening the frame of the elevator, so that the side boards may be diminished in thickness much more than the amount of the thickness of the said lining-sheets, whereby, the space within the elevator and the width of 65 the elevating-belts being undiminished, the entire width of the harvester-frame from front to rear may be diminished from one to two inches, saving that amount of metal in all bars and shafts extending fore and aft through 70 out the entire machine.

I find that by making these metallic lining-sheets of about No. 18-gage steel-plate I can dispense entirely with the side boards, the steel-plates, together with the corner-posts 75 and the canvas-slides, affording all the strength and rigidity required.

I claim—

In a harvester - elevator, in combination with the elevator-frame and the canvas-slides, 80 a metallic sheet-lining located interiorly to the frame and exteriorly to the canvas-slides and secured by bolts passing through the supporting-posts of the frame and through the canvas-slides, substantially as set forth. 85

In testimony whereof I have hereunto set my hand, this 15th day of October, A.D. 1886, at Chicago, Illinois, in the presence of two witnesses.

JAMES E. DEERING.

Witnesses:

J. F. STEWARD,
P. D. MIDDLEKAUFF.
